WALL-TYPE CONTAINER FOR TOOTH BRUSHES

Raymond W. Alves, Woodside, Calif.

Application February 18, 1954, Serial No. 411,098

3 Claims. (Cl. 312—206)

The present invention relates to improvements in a wall-type container for tooth brushes. It consists of the combinations, constructions, and arrangement of parts, as hereinafter described and claimed.

As the cardinal object of this invention, it is proposed to provide a container of the character described, which may be readily mounted on a wall of a bathroom, or the like, with a forward portion of the container being exposed in the room, while the remainder thereof is effectively concealed within the wall. Moreover, this container is adapted to hold a plurality of tooth brushes, maintaining them in a sanitary condition, yet permitting the brushes to be withdrawn individually.

Another object is to provide a container for tooth brushes, which is fashioned with a depressed forward portion arranged for the accommodation of the bristles of the brushes. This portion is made in such a manner that it may be easily cleaned, well ventilated, and so constructed that the brushes may be inserted into or withdrawn from the container with facility and ease.

A still further object is to provide a slotted face plate, which may be installed over an opening formed in a building wall, and so designed that the housing of the container may be anchored to this face plate, with a portion of the housing extending into the wall itself.

Other objects and advantages will appear as the specification continues. The novel features of the invention will be set forth in the claims hereunto appended.

Drawing

For a better understanding of my invention, reference should be had to the accompanying drawing, forming part of this application, in which:

Figure 1 is a side elevational view of my wall-type container for tooth brushes, disclosing it as being mounted on a building wall, parts being shown in section;

Figure 2 is a longitudinal vertical sectional view taken through the midportion of the same container and wall;

Figure 3 is a transverse sectional view taken along the vertical plane III—III of Figure 2; and

Figure 4 is a front elevational view of the device, as observed from the left hand side of Figure 1.

While I have shown only the preferred form of my invention, it should be understood that various changes, or modifications, may be made within the scope of the annexed claims without departing from the spirit thereof.

Detailed description

Referring to the drawing, it will be noted that I provide a housing indicated generally at A, which is fashioned with a compartment B. The latter is dimensioned to have a plurality of tooth brushes C inserted thereinto in substantially parallel relation with one another. Broadly speaking, this compartment defines an elevated rear portion B1 adapted for receiving the handles 10 of the brushes; and further provides a depressed forward portion B2 arranged for accommodation of the bristles 11 of the brush heads 12. An upwardly-extending wall 14

2

is disposed between the bottoms of the depressed and elevated portions, thereby precluding moisture in the former from draining into the latter.

As shown in Figure 2, the housing A has an opening 15 in the forward portion thereof giving access to the compartment B. This opening defines an inclined marginal rim 16 extending diagonally across intermediate sections of the brush heads 12, when the brushes are disposed in the compartment, thereby leaving parts of the brush heads positioned for manual grasping. The housing has a wall 17 at the bottom of the depressed portion B2, and the inclined rim 16 extends downwardly to this wall, thereby facilitating the cleaning of this portion of the compartment.

For the purpose of providing a closure over the opening 15, I make use of a cover D, which is hinged at 18 to the housing. This cover has inclined sides 19 disposed for resting on the marginal rim 16, when the cover is closed. Upon raising the cover, as shown in Figure 2, substantially unobstructed access may be had to the depressed portion B2. A handle 20 has been disclosed on the cover D to permit the latter to be raised or lowered.

It will be realized, of course, that the brushes C may be placed in the housing while still wet from being washed. Accordingly, ventilating and drainage openings 21 are fashioned in the bottom wall 17. Moreover, additional vent openings 22 are formed in the cover D to aid in the circulation of air over the bristles of the tooth brushes.

In order to facilitate the manufacturing of the housing A, the latter has been shown as being made in upper and lower parts A1 and A2, respectively. These parts are abutted one against the other and are secured together by screws 23. Dowel pins 24 may be provided for assisting in aligning one part with respect to the other (see Figure 3).

Reference is made to Figures 1, 2 and 3, wherein it will be observed that partitions 25 are arranged in the elevated portions B1 of the compartment B so as to separate adjacent tooth brushes C. It is preferable that these partitions do not extend into the depressed portion B2, and thereby the latter may be cleaned more readily after raising the cover D and removing the brushes.

Although I do not desire to be limited in respect to the type of wall to which my container may be applied, I have shown a wall E in Figures 1 and 2. As illustrated, this wall includes sheet rock 26 having tile 27 secured thereto by "mud" 28. This tile is provided with an opening 29, which registers with openings 30 and 31 formed in the sheet rock and "mud," respectively.

When using this type of wall construction, a slotted face plate F is mounted over the tile opening 29, and has serrated anchoring prongs 32 projecting from the back of the plate into the "mud." It is quite apparent that screws may be utilized for securing the plate F directly against other types of walls, such as wood, plaster board or sheet rock.

As clearly disclosed in Figures 1 and 2, the housing A may be telescoped through a slot 33 in the face plate F, with the housing extending through the openings 29, 30 and 31. Moreover, the exterior of this housing has a vertical shoulder 34 thereon, which is adapted to abut the plate F to thereby limit the inward telescoping of the housing relative to the building wall E.

An anchoring rod 35 is fixed to the face plate so as to project forwardly therefrom into a bore 36, the latter extending inwardly into the housing part A2 from the shoulder 34. A set-screw 37 is provided for removably securing the rod 35 in the bore 36.

Various attachments may be supported on the housing. For instance, a tube 38 of tooth paste has been

shown as being held against the underneath surface of the bottom wall 17 by a pair of spring arms 39. The latter may be anchored to the wall 17 by screws 40. As shown in Figures 2 and 4, the forward ends of these arms may be interconnected by a bar 41 extending therebetween, this bar being provided with an operating knob 42. The latter may be depressed to allow the tube of tooth paste to be withdrawn.

I claim:

1. In a wall-type container for tooth brushes: a housing provided with a compartment therein, which is dimensioned to have a plurality of tooth brushes inserted therewith; a slotted face plate mounted over an opening provided in a building wall; the housing having a rear portion telescoped through the slot of the face plate and the opening in the building wall; the housing further having a forward portion projecting in front of the building wall; an anchoring rod fixed to the face plate and being telescoped into a bore fashioned in the housing; and means removably securing the housing to the anchoring pin.

2. In a wall-type container for tooth brushes: a housing provided with a compartment therein which is dimensioned to have a plurality of tooth brushes inserted therewith; a slotted face-plate mounted over an opening provided in a building wall; the housing having a rear portion telescoped through the slot of the face-plate and the opening of the building wall; means anchoring the housing to the face-plate; the compartment defining an elevated rear portion for receiving the handles of the brushes, and providing a horizontally-arranged bottom wall; the compartment further having a depressed forward portion arranged for accommodation of the bristles of the brushes; the depressed portion providing a bottom wall disposed below the level of the bottom wall of the elevated rear portion; the housing providing an upwardly-

35

extending wall disposed between the bottom walls of said portions to thereby preclude liquid from draining from the forward bristle-receiving portion of the compartment to the rear handle-receiving portion thereof.

3. In a wall-type container for tooth brushes: a housing provided with a compartment therein which is dimensioned to have a plurality of tooth brushes inserted therewith; a slotted face-plate mounted over an opening provided in a building wall; the housing having a rear portion telescoped through the slot of the face-plate and the opening of the building wall; means anchoring the housing to the face-plate; the compartment defining an elevated rear portion for receiving the handles of the brushes, and providing a horizontally arranged bottom wall; the compartment further having a depressed forward portion arranged for accommodation of the bristles of the brushes; the depressed portion providing a bottom wall disposed below the level of the bottom wall of the elevated rear portion; the housing providing an upwardly-extending wall disposed between the bottom walls of said portions to thereby preclude liquid from draining from the forward bristle-receiving portion of the compartment to the rear handle-receiving portion thereof; the housing having partitions confined to the elevated portion thereof to separate the tooth brushes from one another; the bottom wall of the forward bristle-receiving portion being unobstructed by said partitions to thereby facilitate cleaning of this portion of the compartment.
